T. H. EDELBLUTE

CAR REPLACER

Filed Oct. 10, 1923

UNITED STATES PATENT OFFICE.

THOMAS H. EDELBLUTE, OF PITTSBURGH, PENNSYLVANIA.

CAR REPLACER.

Application filed October 10, 1923. Serial No. 667,648.

To all whom it may concern:

Be it known that I, THOMAS H. EDELBLUTE, a citizen of the United States, residing at Pittsburgh, in the county of Allegheny and State of Pennsylvania, have invented certain new and useful Improvements in Car Replacers, of which the following is a specification.

This invention is for a car replacer, and 10 relates particularly to a car replacer for use in and around the railroads in mines and other earth working operations, although it is not confined to such use.

The invention relates more particularly to 15 that type of car replacer arranged to straddle the rail, and it has for one of its objects to provide, on the under or rail engaging surface of the replacer, and between the ends of the replacer, a curved seat for 20 engagement with the rail which will allow the plate to adjust itself within a certain range, to any inclination it may assume and which may be necessary, in order that the replacer may have a solid seat on the rail 25 when applied to rails of different heights, or when the lower end is forced or moved down below or used above a normal ground line. This surface is also so arranged on the plate as to allow the upper or rearward end of the 30 plate to rock downwardly when the wheel has been raised above the top of the rail, in order to gradually ease the wheel down onto the rail and greatly reduce the distance which the wheel will drop in moving off the 35 plate onto the rail. This will save unnecessary damage to the journal brasses of the heavy mine locomotives.

Obviously, where the plate must be free to rock on the rail, the usual unsatisfactory 40 method of spiking the replacer to a tie is not practical, and my invention includes, in combination with the replacer which may rock, means for clamping the replacer to the rail without interfering with the rocking of the plate.

This is of great advantage in that, due to the increasing number of metal ties being used in mines, spiking is not always possible. Furthermore, where the replacer must be 45 positioned so as to cooperate with the ties,

it may not always be placed close to the car wheels, which is an obvious disadvantage.

My invention may be readily understood by reference to the accompanying drawings, in which:

Fig. 1 is a plan view of a replacer embodying my invention;

Fig. 2 is a side elevation thereof;

Fig. 3 is a longitudinal section in the plane of line III—III of Fig. 1;

Fig. 4 is a transverse section in the plane of line IV—IV of Fig. 1;

Fig. 5 is a similar section in the plane of line V—V of Fig. 1; and

Fig. 6 is a plan view of a two-ended 55 clamping cam that may be substituted for the one shown in the other figures.

The car replacers are sold and used in pairs, one is commonly called the left hand one, and one the right hand one. I have 70 illustrated only the right hand one, as structurally they are similar, the left hand one being a reversal, side for side of the right one.

In the drawings, 5 designates generally 75 the car replacer which is in the form of a plate having two downwardly inclined wings 6 and 7 respectively, separated from each other by opening 8, the plates being joined at their upper ends by a substantially 80 level bridge part 9. The plates are of increasing width downwardly. On the outer edge of the outer wing 6 is a flange or rib 10 which extends the whole length of the replacer and which traverses, at its upper 85 portion, the bridge part 9.

On the outer edge of the wing 7 is a similar rib or flange 11 that begins at the bottom of the rib and terminates some distance to the rear of the uppermost end of 90 the rib 10. The two ribs converge toward their upper ends, but do not meet. They are gradually curved to guide a wheel gradually toward a rail which would be straddled by the plate, as hereinafter more 95 fully described.

The under face of the bridge part 9, which is the part adapted to rest on the rail and support the plate, is longitudinally curved or convexed, the greatest thickness 100

- of metal being between the two ends of the bridge, as designated at 12, the thickness of the plate decreasing gradually to a minimum thickness toward the rear end designated 13. 6 While the metal also decreases in thickness toward the inner end of the bridge, this decrease is not as decided as the decrease in the opposite direction, as clearly shown in Fig. 3.

On the under surface of the plate are 10 longitudinally extending strengthening ribs 14 and transversely extending strengthening ribs 15.

The upper end of the plate has a groove 16 therein which decreases in width toward the 15 end of the plate and increases in depth. This groove is for the purpose of receiving and guiding the flange of the car wheel.

Projecting out from the outer side of the upper end of the plate is a platform 17 having 20 an opening therein through which passes a bolt 18 that pivotally supports a cam plate 19 having an eccentric cam face 20 for engagement with the head of a rail. This cam plate is carried close to the under surface 25 of the platform, so that when the replacer is supported on a rail, it is insured that the cam may be brought into engagement with the head of the rail.

In operation, the plate is placed astraddle 30 the rail, indicated as X in Figs. 3 and 4, with the bridge part resting on the rail and the wider end on the ground or on a tie, as close to the car or locomotive wheels as possible. Due to the convexed surface on 35 the rail engaging part of the bridge, the plate may be inclined within certain limits, to any angle, depending on the height of the rail or the height of the rail head above the ground, and yet have a true bearing 40 surface on the rail at various angles, the point of contact being confined to a relatively small arc. The cam plate 19 is then driven into clamping relation with the head of the rail, securing the replacer in place.

45 When the wheel of the derailed car or locomotive is moved up the plate, it rolls on its flange, and the ribs 11 or 10, depending on the side of the rail it is on, guides the wheel. After the wheel has moved beyond 50 the point of contact between the rail and replacer, and the flange is being guided by groove 16, the weight of the locomotive will cause the plate to rock, bringing the extreme upper end of the plate down onto the rail. 55 By reason of the upper end portion being tapered, the final drop of the wheel onto the rail will be very slight, thereby eliminating a great deal of shock that is, with most of the present commercial types now in use, 60 put on the journals and journal brasses of the cars and locomotives. The clamp will not interfere with the rocking movement of the plate, but will, because of the enormous weight of the cars and the leverage 65 through which it is applied, allow the plate

to rock. The plate, however, is effectively held against movement, the cam having its shortest radius toward the lowermost end of the plate, so that the cam tends to clamp the rail more firmly upon pressure being exerted in the direction which the wheels must move in being replaced.

If the cam engaged the web of the rail instead of the head, the cam might interfere with the rocking of the plate. Furthermore, in and around mines, or other temporary workings, débris and dirt are apt to become lodged around the rail head, and which would interfere with the rapid placing of the replacer, if it were necessary to 70 clamp it to the web of the rail. While this is of advantage, I do not necessarily limit myself to such arrangement.

The replacer may be made in different sizes, and each size may be designed to fit 75 any rails within a certain limit. When the plate is applied to the smallest size rail of the group it is designed to fit, it would, if it were not for the eccentric clamp, have considerable freedom of movement 80 with respect to the rail. However, the cam serves to always set the plate so that the terminal thereof is properly positioned with respect to the gauge line.

Instead of having a single cam for engagement with the various sizes of rails, a 85 double-ended cam 20^a, as shown in Fig. 6, may be used. This will enable the clamp to work efficiently over a wider range. The cam surface at one end is struck from a greater radius than the one at the other end.

In some cases, as where the wheels of the locomotive or car are in soft earth, the upper end of the plate may have a tendency to lift 100 up when the wheels first begin to climb the replacer. In order to positively limit such upward movement, in the event the cam should not hold, the cam may have a lip 20' thereon which projects under the head of the rail.

The replacer may be manufactured in various sizes, for use on the smaller sizes, medium and heavy size rails, depending on the service to which the replacer is to be put.

110 I claim as my invention:

1. A car replacer comprising a plate designed to straddle a rail and having spaced apart inclined wings joined together at their upper ends by a bridge portion, said bridge portion having a convexed rail engaging surface on the under side thereof, said bridge having an inclined face on the under side thereof extending from the convexed surface to the end of the plate, whereby the uppermost end of the plate 115 may rock downwardly onto a rail after a wheel has moved past the convexed surface.
2. A car replacer comprising a plate having wheel guiding wings thereon and a convexed rail engaging portion, said por- 120

tion enabling the plate to rock on the rails, said convexed rail engaging portion being disposed intermediate the opposite ends of the plate and spaced inwardly from each end.

3. A car replacer comprising a plate having wheel guiding wings thereon and a convexed rail engaging portion, said portion enabling the plate to be rocked on a rail, and means for clamping said plate to a rail.

4. A car replacer comprising a plate having wheel guiding wings thereon and a convexed rail engaging portion, said portion enabling the plate to be rocked on a rail, and means on the plate for clamping the plate to the head of a rail.

5. A car replacer comprising a plate having wheel guiding wings thereon and a convexed rail engaging portion, said portion enabling the plate to rock on the rails, said convexed rail engaging portion being disposed intermediate the opposite ends of the plate and spaced inwardly from each end, and means for clamping said replacer to the rail to hold it against longitudinal movement, said means enabling the plate to be rocked.

6. A car replacer comprising a plate narrow at one end and wide at the other, said plate having the wider end bifurcated to provide two spaced apart rings connected by the narrow end of the plate, said plate thus being designed to straddle a plate, rail guiding means on the wings terminating at one side of the narrow end of the plate, which side is adapted to fall along the gauge line of the rail with which the replacer is used, a longitudinal rib on the under side of the plate adapted to fall along the gauge line, an integral platform projecting laterally from the top of the plate, and a swinging cam carried on a vertical pivot at the outer part of the platform, said cam having an eccentric periphery directed toward said rib on the under side of the plate, a rail receiving space being provided between said rib and said cam, said cam serving to hold said rib against the gauge line of a rail.

7. A car replacer comprising a plate in the form of two spaced apart inclined wings of upwardly and rearwardly diminishing width joined at their upper ends by

a substantially level narrow bridge portion, the under surface of the said bridge portion being convexed between its ends and the bridge being of decreasing thickness from the thickest part of the convexed area to the rearmost end of the plate, said convexed surface enabling the plate to rock on a rail, an extension at one side of the bridge, and an eccentric rail engaging cam carried by said extension on a vertical pivot for clamping the plate to a rail, the cam being so curved that longitudinal pressure in a rearward direction forces the cam into a tighter engagement with a rail, the plate having wheel guiding means on its upper surface.

8. A car replacer comprising a plate adapted to straddle a rail and having a slot therein in which the rail may be received, said slot being sufficiently wide to receive rails of a plurality of different sizes, said plate having an outside wing and an inside wing, and a bridge connecting the upper ends of the wings and adapted to rest on a rail, both of said wings sloping downwardly from the bridge, a rib on the upper surface of the inside wing terminating in proximity to the bridge, a rib on the top of the outside wing that extends diagonally across the bridge, the inner side of the bridge having a short flange receiving groove therein alongside the rib and being adapted to fall in line with the gauge line of a rail, and a clamp alongside the bridge and in transverse alignment therewith carried by the plate for engaging a rail and arranged to always bring the inside edge of the bridge into line with the gauge line irrespective of the width of the rail.

9. A car replacer comprising a plate adapted to be placed astraddle a rail and having wheel guiding surfaces thereon, and a clamp for securing the plate to a rail comprising a double-ended eccentric cam pivotally carried by the plate and having the cam surface at one end thereof struck from a greater radius than the one at the other end, whereby said replacer is applicable to rails of varying sizes.

In testimony whereof I affix my signature.

THOMAS H. EDELBLUTE.
